(57) **CLAIM**

The ornamental design for a gaming die, as shown and described.

DESCRIPTION

FIG. 1 is an elevated perspective view of a gaming die in accordance with the present invention;

FIG. 2 is a front side view thereof;

FIG. 3 is a bottom view thereof, with part of the environment (the cylinder on the bottom of the die) removed; and,

FIG. 4 is a top view thereof, with part of the environment (the potion bottle stopper on the top of the die) removed. The left, right, and back side views (not individually shown) are mirror images of the front side view shown in FIG. 2. The broken lines forming trapezoids on the sides of the die, and the broken lines on the top of the die, represent boundaries which form no part of the claimed design.

All other broken lines (the numerical symbols on the sides of the die, the cylinder on the bottom of the die, and the potion bottle stopper on the top of the die) represent environment and form no part of the claimed design.
